UNITED STATES PATENT OFFICE.

FRED R. KUNKEL, OF WILKINSBURG, PENNSYLVANIA. ASSIGNOR TO WESTINGHOUSE ELECTRIC & MANUFACTURING COMPANY, A CORPORATION OF PENNSYLVANIA

COIL-WINDING MACHINE.

No. 882,253.

Specification of Letters Patent. Patented March 17, 1908.

Application filed June 12, 1905. Serial No. 264,871.

To all whom it may concern:

Be it known that I, FRED R. KUNKEL, a citizen of the United States, and a resident of Wilkinsburg, in the county of Allegheny and State of Pennsylvania, have invented a new and useful Improvement in Coil-Winding Machines, of which the following is a specification.

My invention relates to means for facilitating the winding of longitudinally slotted, cylindrical cores for dynamo electrical machinery and has special reference to the winding of two-pole armature cores that are provided with partially closed slots.

The object of my invention is to provide means for rotatably mounting and winding cylindrical armature cores that shall be simple and durable in construction and easy of application and that shall effectually guide the winding conductor into a pair of predetermined slots.

By the use of my invention, the winding of armatures having partially closed slots is materially facilitated, since provision is made for rotatably mounting the armature so that the winding plane is substantially vertical and perpendicular to the axis of rotation and since guide flanges are arranged to guide the conductor into the proper slots.

My invention is illustrated in the accompanying drawings, in which Figure 1 is an elevation of a winding jig constructed in accordance therewith; and Fig. 2 is a plan view, the jig being shown partially in section to disclose an armature core in position.

Referring to the drawings, a cylindrical core 1, which is provided with a shaft 2 and has a plurality of partially closed slots 3, 4, 5, 6, 7, 8, 9, 10, 11, 12, 13 and 14, is rotatably mounted in and supported by a jig that comprises a head stock 15 which may engage a live center on a lathe or similar driving machine, a plurality of flanged guide plates 16 and 17 and a tail stock 18 which may engage the bed-plate of a lathe or be otherwise rigidly supported.

The flanged guide plate 16 is supported from, and is a part of, the head stock or hub 15, which also supports a plurality of bearing arms 19 and 20, that engage the armature shaft 2, thereby rotatably supporting the armature so that it may be easily re-set after each coil is wound.

The arm 20 is detachable from the head

stock 15 so that a core may be readily removed when wound and be replaced by another similar unwound armature core, while both arms 19 and 20 may be respectively provided with closed bearings 21 and 22, the axes of which are in alinement.

The approximately semi-cylindrical flange plate or cap 17 is rigidly attached to a shaft or spindle 23 which is mounted in a bearing 24 in the tail stock 18 and is forced against the core by a spring 24^a, the end play of the shaft being limited by a pin 25, which is held in engagement with any one of a plurality of annular grooves 26 and 27 in the shaft 23 by a spring 28.

The guide plates 16 and 17 together form a substantially closed hollow cylinder but are separated slightly and their edge flanges diverge outwardly, so that two slots 29 and 30 are formed between the two, in the same vertical plane and are so arranged that when the armature is in position they lead directly into a couple of slots, such, for example, as the slots 3 and 8.

The armature core is prevented from rotation on its axis during the winding process by a pin 31 which is mounted in the body of the guide plate 16 and is held in engagement with one of the core slots by a spring 32.

The bearing arm 20 is held in position when the armature 1 is in place by any convenient means such as a hinge-bolt 33, which is attached to the head stock 15 and engages a slot 34 in the detachable portion of the arm, and a thumb-nut 35.

After one end of a core shaft has been placed in the bearing 21, the bearing 22 is slipped over the opposite end and clamped in place. Then pin 31 is moved into engagement with one of the armature slots and the flanged plate 17 is permitted to engage the surface of the core, the center line of the tail stock bearing being coincident with that of the head stock.

An insulated conductor may now be fitted into the slots 29 and 30 as the guide plates and the armature core are rotated together. When a sufficient number of turns for a single coil has been completed, the armature is rotated until the pin 31 engages another slot. This process is continued until the winding is complete.

It is usually found desirable to successively wind coils which are on opposite sides

of a central plane of the core, so that when the winding is complete, the armature will be substantially statically balanced.

Although I have, for convenience, shown a specific arrangement applied to a core having twelve slots, I desire that my invention shall include within its scope any other arrangement or structure which does not depart materially from the purpose set forth or the results attained.

I claim as my invention:

1. The combination with a rotatable member comprising two bearings, the axes of which are in alinement and are perpendicular to the axis of rotation of said member, of two segmental guide plates, one of which is a part of said member, while the other is rotatably mounted upon a separate base.

2. The combination with a rotatable driving member that comprises two bearings, the axes of which are in alinement and are substantially perpendicular to the axis of rotation of said member, and a semi-cylindrical plate, of a second complementary plate that is rotatably mounted on a separate base, both of said rotatable plates having a common axis of rotation.

3. A rotatable winding device for slotted armature cores comprising a plurality of shaft bearings, the common axis of which is perpendicular to the axis of rotation of said device, means for guiding a conductor into a predetermined pair of core slots as said core is rotated, and means for engaging any one of the core slots to lock the core in the winding device.

4. A rotatable winding device for longitudinally slotted cylindrical cores comprising a plurality of bearings, the common axis of which is perpendicular to the axis of rotation of said device, means for guiding a conductor into a predetermined pair of core slots as said core is rotated, and a locking pin that engages a core slot to prevent the core from rotating on its axis.

5. A rotatable winding device for slotted

armature cores comprising a fixed shaft-bearing and a detachable shaft-bearing having a common axis which is perpendicular to the axis of rotation of said device, means for guiding a conductor into a predetermined pair of core slots as said core is rotated, and a locking device that engages one of the core slots.

6. A rotatable winding device for slotted armature cores comprising a fixed shaft-bearing and a detachable shaft-bearing having a common axis which is perpendicular to the axis of rotation of said device, means for guiding a conductor into a predetermined pair of core slots as said core is rotated, and means that engages a core slot to prevent the core from rotating on its axis.

7. A rotatable winding device for slotted armature cores comprising a plurality of shaft-bearings, the common axis of which is perpendicular to the axis of rotation of said device, and means for guiding a conductor into a predetermined pair of core slots as said core is rotated that comprises a pair of complementary and substantially semi-cylindrical caps held adjacent to but out of engagement with the core and having diverging flanges.

8. A rotatable winding device for slotted armature cores comprising a plurality of shaft-bearings, the common axis of which is perpendicular to the axis of rotation of said device, means for guiding a conductor into a predetermined pair of core slots as said core is rotated that comprises a pair of complementary and substantially semi-cylindrical plates having diverging flanges, and means for engaging a core slot to prevent the core from rotating on its axis.

In testimony whereof, I have hereunto subscribed my name this 6th day of June 1905.

FRED R. KUNKEL.
